ARTHUR E. PETERS, OF LITTLETON, COLORADO, ASSIGNOR TO INGERSOLL-RAND COMPANY, OF JERSEY CITY, NEW JERSEY, A CORPORATION OF NEW JERSEY.

DOLLY RETAINER.

Application filed February 11, 1927. Serial No. 167,575.

This invention relates to drill sharpeners, but more particularly to a dolly retainer for fluid actuated drill sharpeners and the like.

One object of the invention is to protect the dolly spring against the effects of the different stresses to which said spring is subjected during the reciprocation of the dolly, thus lessening the chances of breakage in retainers of this type.

10 Other objects will be in part obvious and in part pointed out hereinafter.

The invention consists of the combination of elements and arrangement of parts substantially as hereinafter described and 15 claimed and illustrated in the accompanying drawings, in which

Figure 1 is a sectional view in elevation of a portion of a drill sharpener showing the retainer applied thereto,

20 Figure 2 is an end elevation, and

Figure 3 is an elevation in section taken through Figure 1 on the line 3—3 looking in the direction indicated by the arrows.

Referring to the drawings, in which only 25 so much of a drill sharpener is shown as will serve to illustrate the invention and its application, a cylinder A supports a front head B and is provided with a reciprocatory hammer piston C. The hammer piston C has a

30 plain forward extension D slideable through a front cylinder washer E and is adapted to reciprocate into a bore F of the front head B. Disposed slidably in the front end of the front head B is a dolly H having a reduced 35 rearward extension J which projects into the bore F of the front head B to receive the blows of the hammer piston C. Preferably a port G is formed in the front head B to prevent the formation of a cushion in the bore F.

The outer or forming face K of the dolly H may be of any suitable formation to form a corresponding face on the end of a drill steel (not shown) and which drill steel may 45 be securely held in operative position by suitable devices independent of the drill sharpener. It is, however, to be understood that the dolly illustrated in the drawings does not form any part of the invention and is 50 shown only for illustrative purposes.

Suitable means are provided for insuring the retention of the dolly in the front head B. These means in the present instance comprise a U-shaped loop L consisting of a pair 55 of converging legs P connected by an inte-

gral intermediate portion Q which, in its operative position, is adapted to lie in and engage a transverse slot H' in the periphery of the dolly H.

In order to produce the necessary tension 60 on the loop L to hold the dolly H normally in retracted position, the loop L is provided with a pair of springs R and S which have at their inner ends upwardly projecting exten-

sions T adapted to lie in the same longitudinal plane as the legs P of the loop L. The outer ends of the springs R and S are in this instance provided with rearwardly extending side arms U carrying at their rearward ends hooks V to engage pivotal trunnions W preferably carried by the front head B.

The trunnions W are so spaced with respect to a flange X on the front head that only sufficient clearance exists between the trunnions and said flange to enable the hooks V to be hooked over the trunnions W. With the trunnions W thus located on the front head, the hooks, in their operative position, will bear against the flange X and will be held thereby against unintentional displacement from the trunnions.

Heretofore, springs of this type when employed for the purposes described have been incapable of rendering service for any considerable period of time, the reason for this 85 being that springs formed of wire of sufficiently small diameter to provide the necessary resiliency are usually incapable of withstanding the various stresses to which such springs are subjected during the operation of the sharpener.

The present invention entirely eliminates such breakage of the dolly springs and for this reason the retainer is formed of separate members held and guided in operative position by suitable guide couplings designated generally by Y. The outer casings or guide sleeves Z of the couplings Y are provided at each end with relatively large recesses b divided by an intermediate wall c. In opposite sides of the walls c are formed small recesses d to receive the ends of the legs P and the extensions T. In this way the adjacent ends of the said legs and extensions are held coaxially with respect to each other.

In order to form a suitable pliant guide for the legs P and the extensions T, fiber bushings e are disposed in the recesses b and have bores f to receive slidably a portion of said legs and extensions at points near the

adjacent extremities of these elements. The fiber bushings *e* are preferably of somewhat smaller diameter than the recesses *b* to enable rubber tubes *g* to be disposed about the said bushings for the purpose of cushioning such relatively angular movement as may occur between the legs *P* and the extensions *T* during the reciprocations of the dolly *H*.

In the present instance the bushings *e* and the tubes *g* are of somewhat less length than the recesses *b* to enable the ends *h* of the sleeves *Y* to be crimped over the ends of the bushings for the purpose of retaining said bushings and said tubes in the recesses. The ends *h* of the sleeves *Y*, however, are preferably spaced a sufficient distance from the legs and extensions to enable said legs and extensions to move freely in a lateral direction within the recesses *b* without interference from the ends *h*.

The relative angular positions of the extensions *T* and the side arms *U* is preferably such that when the loop *L* is disposed in the slot *H'* and the hooks *V* are anchored on the trunnions *W*, a considerable tension will be set up in the springs *R* and *S* tending at all times to force the dolly *H* to its rearwardmost limiting position in the front head *B*.

The present invention has been found to function in an unusually efficient manner and, owing to the resilient couplings which connect the loop *L* to the springs *R* and *S*, breakage of the retainer has been entirely eliminated.

In assembling the retainer on the drill sharpener, the hooks *V* are first disposed on the trunnions *W* and the loop *L* may then be deflected outwardly away from the sharpener to a position to enable the portion *Q* of the loop to be inserted in the slot *H'* of the dolly *H*, it being of course understood that the dolly *H* will then be partly withdrawn from the front head. After the loop has been thus inserted in the slot *H'*, the spring, together with the dolly, may be released and the spring will, due to the tension set up therein, carry the dolly rearwardly into the front head to a position to receive the blows of the hammer piston *C*.

I claim:

1. A retainer for a dolly comprising a loop adapted to engage the dolly, a spring for normally holding the dolly in retracted position, means for anchoring the spring to a drill sharpener, and flexible connecting means connecting the spring to the loop.

2. A retainer for a dolly comprising a loop adapted to engage the dolly, a separate spring for normally holding the dolly in retracted position, means for anchoring the spring to a drill sharpener, and removable flexible connecting means connecting the spring to the loop.

3. A retainer for a dolly comprising a loop adapted to engage the dolly, a separate spring holding the dolly normally in retracted position, means on the spring for anchoring said spring to a drill sharpener, and flexible connecting means connecting the end of the spring to the leg of the loop.

4. A retainer for a dolly comprising a loop adapted to engage the dolly, a spring holding the dolly normally in retracted position, means on the spring for anchoring said spring to a drill sharpener, and yieldable connecting means connecting the spring to the loop.

5. A retainer for a dolly comprising a loop adapted to engage the dolly, a spring holding the dolly normally in retracted position, means on the spring for anchoring said spring to a drill sharpener, and transversely yieldable connecting means connecting the spring to the loop.

6. A retainer for a dolly comprising a loop adapted to engage the dolly, springs holding the dolly normally in retracted position, side arms integral with the springs for anchoring said springs to a drill sharpener, and yieldable connecting means connecting the springs to the loop.

7. A retainer for a dolly comprising a U-shaped loop to engage the dolly, springs normally holding the dolly in retracted position, extensions at one end of the springs, side arms at the other end of the springs anchoring the springs to a drill sharpener, and connecting means forming flexible connections between the extensions and the terminals of the loop.

8. A retainer for a dolly comprising a U-shaped loop to engage the dolly, coil springs holding the dolly in retracted position, extensions at the inner ends of the coil springs, side arms at the outer ends of the coil springs for anchoring the coil springs to a drill sharpener, and sleeves connecting the legs of the loop to the spring extensions.

9. A retainer for a dolly comprising a loop adapted to engage the dolly, springs holding the dolly normally in retracted position, side arms integral with the springs for anchoring said springs to a drill sharpener, sleeves connecting the ends of the loop to the springs, and yieldable means in the sleeves to permit relative angular movement between the springs and the loop.

10. A retainer for a dolly comprising a U-shaped loop to engage the dolly, said loop having converging legs, springs holding the dolly normally in retracted position, extensions on the springs, arms on the springs having hooks for anchoring the springs to a drill sharpener, sleeves holding and guiding the extensions and the said legs normally coaxial with respect to each other, yieldable means in the sleeves to cushion relative angular movement between the legs and the ex-

tensions, and means in the sleeve holding the adjacent ends of the legs and the extensions against relative transverse movement.

11. A retainer for a dolly comprising a U-shaped loop to engage the dolly, said loop having converging legs, springs holding the dolly normally in retracted position, extensions on the springs, arms on the springs having hooks for anchoring the springs to a drill sharpener, sleeves to receive the extensions and the legs, bushings in the sleeves slidably guiding the extensions and the legs, and rubber tubes encircling the bushings to cushion relative angular movement between the extensions and the legs.

12. A retainer for a dolly comprising a U-shaped loop to engage the dolly, said loop having converging legs, springs holding the

dolly normally in retracted position, extensions at the inner ends of the springs, arms at the outer ends of the springs having hooks at their terminals for anchoring the springs pivotally to a drill sharpener, sleeves having recesses in their ends for the reception of the extensions and the legs, fiber bushings in the recesses to slidably guide the extensions and the legs, rubber tubes encircling the bushings to cushion relative angular movement between the legs and the extensions, and means in the sleeves holding the adjacent ends of the legs and extensions coaxial with respect to each other.

In testimony whereof I have signed this specification.

ARTHUR E. PETERS.
